UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

WINDOW-SASH.

1,256,046.

Specification of Letters Patent.

Patented Feb. 12, 1918.

Application filed December 17, 1913. Serial No. 307,190.

To all whom it may concern:

Be it known that I, HARRY H. SCHROYER, a citizen of the United States, and a resident of the city of Chicago, in the county of Cook 5 and State of Illinois, have invented certain new and useful Improvements in Window-Sashes; and I do hereby declare that the following is a full, clear, and exact description of the same, reference being had to the accompanying drawings, and to the numerals of reference marked thereon, which form a part of this specification.

Window sashes as heretofore constructed have usually been provided with removable bead members whereby the light of glass carried by the sash can be removed or inserted in the sash and retained in position by the beads. The addition of removable beads to a window sash has not only detracted from 15 its appearance, but in instances where metallic sashes have been used for passenger cars the removable beads, which of necessity must also be of metal, have not been entirely successful in operation. The association of a metallic bead with a metallic sash for the purpose of retaining the light of glass in place has involved a number of complicated parts, making the construction expensive 20 and otherwise impractical.

30 This invention relates to a metallic sash construction wherein the top, bottom and side rails of the sash are detachable from one another, and are each provided with retaining beads permanently associated therewith for the light of glass whereby the glass may be inserted or removed from the sash by removal of one of the rail or stile members.

It is an object of this invention to construct a metallic sash embracing tubular detachable side, top and bottom rails, each having means associated therewith to receive a light of glass therein, when the device is assembled.

It is also an object of this invention to provide a metallic sash constructed of tubular detachable members and with means secured within said members for attaching the members together in assembled relation.

It is also an object of this invention to construct a metallic sash of tubular top, bottom and side rails, and with filler blocks contained within said rails and riveted thereto, said rails having integral beads formed thereon adapted to register with one another 50 when the rails are assembled to retain a

light of glass, and with means adjustably connecting said rail members to one another by said blocks, insuring a proper association of the parts.

It is furthermore an object of this invention to construct a window sash having integral beads thereon to receive a light of glass therebetween, and with one of said rails formed to receive a weather-stripping element therein.

It is finally an object of this invention to construct a metallic window sash easily assembled, and of substantial construction, and consisting of few parts.

The invention (in a preferred form) is illustrated in the drawings and hereinafter more fully described.

In the drawings:

Figure 1 is a fragmentary front face view of a portion of the framing for a car window 75 sash embodying the principles of my invention.

Fig. 2 is an interior fragmentary face view of an upper corner of a window sash showing the attaching elements in dotted lines. 80

Fig. 3 is a similar view of a lower corner of a window sash.

Fig. 4 is a section taken on line 4—4 of Fig. 2.

Fig. 5 is a section taken on line 5—5 of Fig. 3.

Fig. 6 is a view similar to Fig. 2, but with the parts shown in section.

Fig. 7 is a section taken on line 7—7 of Fig. 3 with parts in elevation.

As shown in the drawings:

A portion of a car is indicated by the reference numeral 1, and mounted in the window apertures therein are sashes containing the lights of glass 2. The top, bottom and side rails of the sashes are cut at their ends at an angle of 45 degrees, and substantially rectangular in section. Each rail consists of a unitary sheet of metal bent to afford the inner and outer straight walls 3 and 4, respectively, and an end wall 5, and that portion of the metal joining the inner and outer face walls 3 and 4, is shaped to afford the inner and outer beads 6 and 7, respectively, affording a groove therebetween. The 100 groove is to receive the light of glass 2, therein, and, if desired, any suitable packing may be inserted between the glass and the beads to aid in the proper seating of the glass, and to afford a seal.

The construction of the bottom rail is slightly different in that in place of the end wall 5, the metal is stamped to afford a dove tailed groove or recess, as indicated by the reference numeral 8, and clearly shown in Fig. 5. The purpose of said groove 8, is to permit a packing member 9, to be inserted therein and to seal between the sash and the sill of the window frame when the sash is in closed position.

The means for attaching and maintaining the rails of the window sash in assembled relation comprise filler blocks 10, which are secured within and near each end of the top and bottom rails by means of rivets 11. Said filler blocks are further provided with an internally threaded aperture for a purpose hereinafter pointed out.

The side rails of the window sash are provided with filler blocks 12, riveted therein by suitable rivets 13, but in this case the filler blocks extend outwardly through the angled ends of the rail and are furthermore provided with a projecting portion 14, which is adapted to engage within the tubular top and bottom rails respectively when the same are assembled with the side rails. An aperture extends through each of said filler blocks 12, and inserted rotatably through each thereof, is a long machine screw 15, the threaded end of which engages in the threaded aperture in the filler block 10, thus permitting said blocks to be drawn up toward one another and insuring close association of the respective rails of the sash.

From the construction disclosed it is readily seen that the rivets for the filler blocks, as well as the adjusting screws, which are countersunk into the respective rails flush with the surface of the outer walls thereof, form no projections which might interfere with the operation of the sash.

The operation is thought to be obvious from the description. However, when it is necessary to insert or remove a light of glass from the sash it is only necessary to remove one of the rail members and the glass can then be readily slipped along the grooves between the beads 6 and 7.

I am aware that various details of construction may be varied through a wide range without departing from the spirit of this invention, and I therefore do not purpose limiting the patent granted otherwise than necessitated by the prior art.

I claim as my invention:

1. In a window sash hollow side, top and bottom members mitered at their ends to form a tight joint, filler blocks rigidly secured in the ends of each hollow member,

the blocks in two of the members having a threaded aperture and the blocks in the other two members having passages therethrough and screws extending through the passages in said blocks and engaging in the screw apertures to tightly draw the members together in assembled relation.

2. In a window sash hollow top, side and bottom members formed to provide oppositely disposed beads to retain a glass therebetween, independent filler blocks in the ends of all of the members and means extending through the filler blocks in part of the members and engaging the filler blocks in the other members to tightly draw the sash members together.

3. In a window sash structure of the class described, tubular side rails, tubular top and bottom members, filler blocks mounted within said top and bottom members, filler blocks mounted within the ends of said respective side rails projecting therefrom and adapted to interfit with said top and bottom members, and means engaged through the filler blocks of said side rails and having threaded engagement with the filler blocks in said top and bottom members to draw the same tightly to one another in rigid assembled relation.

4. In a window sash structure of the class described, side rails, and top and bottom rails with the ends of each thereof oblique, filler blocks mounted on the interior at each of the ends of each of said rail members, with the filler blocks of the side rails projecting beyond the ends thereof, and means rotatably engaged through the filler blocks of the side rails and adapted for engagement with the filler blocks mounted within said top and bottom rails to draw said respective rail members tightly to one another in assembled relation.

5. In a window sash construction of the class described hollow top and bottom rails, filler blocks secured rigidly within each thereof at each end thereof, hollow side rails, filler blocks secured in said side rails at each end of each thereof, and means adjustably mounted in said filler blocks of said side rails adapted to adjustably engage said filler blocks of said top and bottom rails to draw said respective rails tightly into assembled relation.

In testimony whereof I have hereunto subscribed my name in the presence of two subscribing witnesses.

HARRY H. SCIROYER.
